CLAIM

The ornamental design for a grille for a vehicle, as shown and described.

DESCRIPTION

FIG. 1 is a front, bottom and right side perspective view of a grille showing my new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The broken lines showing mounting features for the grille are included for the purpose of illustrating environmental structures, and form no part of the claimed design.

1 Claim, 6 Drawing Sheets
